UNITED STATES PATENT OFFICE

RICHARD E. FRASER, OF STOCKTON, CALIFORNIA, ASSIGNOR TO FRASER FURNACE COMPANY, OF STOCKTON, CALIFORNIA, A CORPORATION OF CALIFORNIA

GAS IGNITION MEANS FOR GAS FURNACE BURNERS

Application filed March 25, 1929. Serial No. 349,610.

This invention relates to gas burners, especially those used in connection with a heating furnace of that type in which the burner is more or less inaccessible to the operator and the ordinary match lighting operation is not easily carried out.

I have therefore in mind to ignite the gas by an electric spark, and the principal object of my invention is to provide a combination gas control valve and switch structure for the spark device so arranged as to be readily controlled from a remote point, and so constructed that the switch will be closed and a spark formed before the gas is actually turned on.

A further object of the invention is to provide a sparking apparatus so related to the burner that the spark as formed is immediately adjacent the burner, so that the gas will be instantly ignited as soon as it is turned on and emerges from the burner.

I am aware of course that some furnaces of this general character which are now on the market are already provided with electric ignition means for the gas. In all such devices, however, as far as I am aware, the gas is turned on full before the switch is closed, so that a large volume of gas is unavoidably present in the gas chamber and about the burner before the spark is formed.

Also the sparking points, to prevent burning, are usually positioned some distance to one side of the actual normal path of flow of the gas, which further retards the ignition of the gas and necessitates the chamber in which the spark device is located filling up with gas before the same will be ignited. As a result of this arrangement the ignition of the gas when it occurs has practically the effect of a mild explosion.

My improved ignition arrangement, as will be seen hereinafter, avoids both these undesirable features and enables the gas to be ignited the instant it begins to flow from the burner and before any unburnt gas has a chance to fill the chamber.

I have also arranged a simple apparatus to enable the gas to be ignited by a pilot light in the event the electricity fails, with-

out interfering in any way with the control of the gas flow.

A further object of the invention is to produce a simple and inexpensive device and yet one which will be exceedingly effective 55 for the purposes for which it is designed.

These objects I accomplish by means of such structure and relative arrangement of parts as will fully appear by a perusal of the following specification and claim.

In the drawings similar characters of reference indicate corresponding parts in the several views:

Fig. 1 is a side elevation of my improved gas ignition and control mechanism shown 65 in connection with a burner.

Fig. 2 is a top plan view of the gas valve and switch unit detached, and associated with a pilot light valve.

Fig. 3 is a fragmentary cross section of 70 the valve and switch unit taken on the line 3-3 of Fig. 2.

Referring now more particularly to the characters of reference on the drawings, the numeral 1 denotes a gas burner, which is in 75 the form of a hollow casting having a plurality of upstanding jets or nipples 2 and adapted to be removably mounted in an open bottomed casing 3.

A spark plug 5 is mounted in one side of 80 the casing, said plug having only a single centrally disposed and relatively long contact stem 6 which forms one electrode. The other electrode is the adjacent burner jet 7, which jet is not integral with the burner as 85 are the other jets but is of a special and relatively hard metal, as is necessary for its specific purpose.

Connected to the base of the burner is the horizontal mixing pipe 8 of usual character 90 into the outer end of which, beyond one side of the casing, the gas valve 9 projects. This valve is of the standard type for the purpose having a plug 10, a quarter turn of which fully opens or closes the valve. The valve 95 opposite to the mixing pipe is screwed into a manifold 11 to which the main gas pipe 12 is connected. This manifold is supported in a horizontal position from a bracket 13 depending from the adjacent side of the 100

5 casing. The valve is set with its plug in a vertical position and with its operating end upwardly, and formed on its upper end is a horizontal disc 14. A socket member 15 to receive the vertical operating rod 16 which extends up to the top of the furnace is superimposed on the disc; said socket member being turnably centralized on the disc by means of a stem 17 depending into the disc and the adjacent portion of the plug.

10 The sleeve has a radially projecting lug 18 adapted to engage an upstanding pin mounted on the disc but insulated therefrom by a bushing 20. Projecting upwardly from the disc on the opposite side of the lug is a rigid stop pin 21, the lug being normally held against this pin and away from the pin 19 by a spring 22 between the disc and the sleeve; the space between the pin 19 and the lug being then sufficient so as to absolutely prevent the possible jumping of a spark therebetween.

15 The under side of the pin 19 is provided with binding nuts 23 to which a wire 24 is connected; said wire leading to one terminal of a transformer 25 with an induction coil 26 interposed therebetween. The other wire 27 from the transformer is connected 20 to the plug 5.

25 Since there is a continual metal connection from the burner nipple 7 to the sleeve 15 it will be seen that when the lug 18 engages the pin 19 a circuit will be closed 30 through the plug and burner, causing a spark to be formed between the plug contact 6 and the adjacent nipple 7.

35 The valve is arranged to be opened in the direction of rotation of the sleeve 15 toward the pin 19 and it will be seen that with the 40 initial turning movement of the sleeve the lug must engage the pin 19 before any turning movement is imparted to the valve plug. The spark circuit therefore will be closed 45 before any gas is fed to the burner, and since such gas will flow from the nipple 7 as readily as from the other nipples the gas will be instantly ignited by the already present spark.

50 A continued turning movement of the rod and disc in the same direction will of course control the extent to which the valve is opened and the volume of the gas feed to the burner. A release of the turning pressure 55 on the operating rod enables the spring 22 to at once act to pull the lug 18 away from the contact pin 19 and against the stop pin 21, breaking the circuit while leaving the valve in its set position. A rotation 60 of the rod in the opposite direction causes the lug to bear against the stop pin 21 and turn the disc to a valve closing position without again closing the circuit.

65 To enable the burner to be operated in the event that the electricity fails, which of

course does not interfere with the opening or closing of the gas valve, another gas valve 28 is mounted in the manifold 11 to one side of the valve 9. From this valve a small pipe 29 leads to the burner adjacent the jets, the outer end of this pipe being open and adapted to serve as a pilot jet. The valve is provided with a vertical operating rod 30 so that it may be opened and closed, this valve and its control rod being 75 of course independent of the main valve 9.

70 It will be noted that the burner, the plug and the valves are all below the bottom of the main gas chamber and the bottom 31 of the chamber-surrounding casing, so that any 80 or all of these parts may be easily inspected or removed at any time without disturbing the casing or any parts rigidly secured thereto.

85 From the foregoing description it will be readily seen that I have produced such a device as substantially fulfills the objects of the invention as set forth herein.

90 While this specification sets forth in detail the present and preferred construction 90 of the device, still in practice such deviations from such detail may be resorted to as do not form a departure from the spirit of the invention, as defined by the appended claim.

95 Having thus described my invention what I claim as new and useful and desire to secure by Letters Patent is:

100 A combination gas valve and electric switch including a valve member, a turnable plug therein, a disc rigid with the plug, a contact pin upstanding from the disc in offset relation to the plug, a vertical socket member resting on the disc, a stem formed 105 with said member to turnably seat in the disc centrally thereof, said socket being adapted to receive an operating rod in non-turnable but removable relation, and an arm formed with the socket and projecting radially therefrom to engage the contact pin.

110 In testimony whereof I affix my signature.
RICHARD E. FRASER.
